CONTROL DEVICE

Philip S. Russel, Detroit, Mich., assignor to Detroit Lubricator Company, Detroit, Mich., a corporation of Michigan

Application November 23, 1937, Serial No. 176,145

19 Claims. (Cl. 137—68)

My invention relates generally to control devices and more particularly to gravity feed, constant liquid level controls.

It is an object of my invention to provide a new and improved liquid level control device in which clogging of a port by foreign matter is prevented.

Another object of my invention is to provide a new and improved liquid level control device in which a valve, controlling a port to maintain a constant liquid level in a chamber, is operated in a manner to automatically keep the port free of clogging material.

Another object of my invention is to provide, in a device of the above mentioned character, new and improved valve actuating mechanism which will, at regular intervals, close the valve with a snap action, and which will operate in this manner and yet maintain a substantially constant liquid level or pressure head in a chamber.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated my invention, in which drawings—

Figure 1 is a top plan view of my control device showing the arrangement of its operating and associated parts;

Fig. 2 is a view of my device shown partly in elevation and partly in cross section taken along the line and in the direction of the arrows 2—2 of Fig. 1;

Fig. 3 is a view in vertical central cross section of a modified form of my control device showing certain parts thereof in elevation;

Fig. 4 is a view shown in cross section of an inlet and another form of valve;

Fig. 5 is a view in vertical central cross section of another modified form of my control device showing the operating parts thereof in side elevation, and

Fig. 6 is a view in section of a still different form of control device embodying my invention.

Referring to the drawings by characters of reference, the numeral 1 designates in general a hollow casing that may include a removable top wall or cover 2 which may be held in place by screws 3 or by other suitable means. The casing 1 has a relatively large outlet chamber 4 for liquid and a relatively small inlet cham-

ber 5. The inlet chamber 5 may be located at one end of the casing 1 within the outlet chamber 4, and may be rectangular in shape as in the present instance. The inlet chamber 5 may be formed by vertical walls 6, 7 and 7^a, together with a portion of the side and bottom walls of the casing 1. Preferably the walls 6 and 7, which may be termed the side walls of the inlet chamber 5, extend longitudinally of the casing 1 in spaced, parallel relation with each other and join with the casing side and bottom walls. Preferably the wall 7^a, which may be termed the end wall of the inlet chamber 5, extends transverse to and joins with the side walls 6, 7 and the bottom wall of casing 1. The walls 6, 7 and 7^a may terminate below the casing cover 2, and the upper end of the inlet chamber 5 is open, as shown.

The chamber 5 has an inlet passage 8, preferably through the bottom wall of the casing 1, and screw threaded into the passage 8 there is preferably provided a removable valve seat member or fitting 9 that projects upwardly within the inlet chamber 5. The bottom wall of the casing 1 may be formed with a depending hollow boss 10, communicating with the inlet passage 8, for connection with a conduit or pipe (not shown) that may connect the inlet to a source of supply of liquid. The inlet 8 preferably extends through an upstanding boss 11 formed integral of the casing bottom wall, and a gasket 12 may be held under compression between the upper end of the boss 11 and an external annular flange 13 of the fitting 9 to insure a fluid tight joint. The fitting 9 may be a tubular shaped, open ended member having a vertically extending passage or bore 14 that may have a reduced bore portion 15, preferably at the lower end of the fitting 9, to provide an upwardly facing port and seat 16 for cooperation with a valve member 17. The valve member 17 is disposed for vertical reciprocal movement in the fitting bore 14, and at its lower end the valve member is preferably formed with a conical face 18 for cooperation with the port 16 to control flow therethrough. The vertical bore 14 of the fitting 9 is of slightly larger diameter than the diameter of the valve member 17 to provide an annular space or chamber for flow of liquid, and opening through the side wall of the fitting 9, within the chamber 5, one or more apertures or bores 20 may be provided for the passage of liquid out of the fitting into the inlet chamber 5. The valve member 17 has a stem portion 21 which projects upwardly above

the upper end of the fitting 9, and fitted over the upper end of the fitting 9 a cap 22 may be provided having an aperture therethrough for slidably receiving and guiding the valve member 17.

A float 23 is disposed in the outlet chamber 4 and is operatively connected to the valve member 17 by a lever member, designated in general by the numeral 24. Intermediate its ends the lever 24 may have downturned side flanges 25 out of which may be formed a pair of spaced lever arms 26. The lever arms 26 may straddle or position one on each side of the inlet chamber side walls 6, 7 and have aligning apertures for receiving pins 27 that may be secured in and to the walls 6, 7 for pivotally supporting the lever 24. The lever 24 may be rigidly secured at one end thereof to the float 23, and the other end of the lever 24 extends into the inlet chamber 5 for connection with the valve 17. Intermediate its ends the lever 24 may have an upwardly directed, offset or bent portion 28 to extend upward over the top of wall 7^a and down into the chamber 5 where an end portion 29 of the lever is preferably in the same horizontal plane as the axis of the pivot pins 27.

The lever end portion 29 in the chamber 5 may be provided therethrough with an elongated aperture or slot 30 for receiving the valve stem 21, and the valve stem may be provided with an abutment 31 in the form of a pin having its opposite ends projecting from the side of the valve stem for abutment against the underside of the lever end portion 29. A resilient plate member or leaf spring 32 may be provided for urging the valve 17 upward to hold the abutment pin 31 in engagement with the lever end portion 29, and the resilient plate 32 may be secured at one end thereof to the underside 40 of the lever end portion 29. It will be understood that the above described connection between the lever 24 and the valve 17 provides for a rocking movement therebetween so that the valve 17 will move vertically with little or no side thrust, but it is also to be understood that the valve and lever may be operatively connected in any other suitable manner.

Carried by the float 23 and preferably mounted on the top thereof there is a receptacle or dump bucket 33 to which liquid is supplied from the inlet chamber 5 and from which the liquid is periodically discharged or dumped into the constant level chamber 4. A duct or conduit 34 may be provided to convey liquid from the inlet chamber 5 to the receptacle 33. One end of the conduit 34 may be secured in and to the side wall 7^a of the inlet chamber 5 and the other end of the conduit may overlie the receptacle 33 to discharge liquid thereinto. The conduit 34 is inclined so that liquid will flow therethrough by gravity to the receptacle 33. The receptacle 33 has a bottom wall 35, an end wall 36 and side walls 37. The receptacle 33 may be hinged at one end thereof, to the float 23, by spaced hinge members 38 which may have a common shaft 39. A tension spring 40 may be provided to determine the weight of liquid in the receptacle 33 that will cause the receptacle to dump the liquid into the chamber 4, and to also return the receptacle to its "up" position after dumping of the liquid therefrom. The spring 40 may be wrapped around the shaft 39 between the spaced hinges 38, with one end of the spring abutting the underside of the receptacle 33 and the other end of the spring abutting the upper

surface of the float 23. The spring 40 acts to pivot the receptacle 33 in a clockwise direction, as seen in Fig. 2, and the hinges 38 may have limited pivotal movement to prevent movement of the receptacle past its "up" position, which position is shown in full lines in the drawings.

The constant level chamber 4 has an outlet port 41 which is preferably formed by the upper open end of a hollow boss 42 that may be integral with the bottom wall of the casing 1 and may project slightly upward within the chamber 4. The upper end of the hollow boss 42 is also provided with a seat for a manually operable valve member 43 that is preferably provided to regulate the rate of flow of liquid from chamber 4. The valve member 43 may have a beveled or conical shaped face 44 for engaging its seat to close the port 41. Below the conical face 44 the valve member 43 preferably has a lower end portion of reduced diameter, as at 45, that is slidably received and guided in an aperture or bore provided through an internal, transversely extending wall 46 of the boss 42, the wall 46 preferably being located adjacent the upper end of the boss. Below the transverse wall 46 the boss 42 has a passage 47 that leads downward through the bottom wall of the casing 1, through an external hollow boss 48 which may be threaded for connection to a supply line or conduit (not shown). The valve member 43 preferably has a metering slot 49 in the side wall of the reduced valve portion 45, and the metering slot may extend longitudinally of the valve. At its upper end the metering slot 49 preferably terminates at a point such that the entire slot will be below the upper surface of the transverse wall 46 when the valve 43 is seated, as shown. When the valve 43 is raised from its seat such that a small portion of the metering slot 49 is above the upper surface of the transverse wall 46, fuel will flow from the chamber 4 through port 41, metering slot 49 into the outlet passage 47, and the rate of flow of liquid will be governed, or will depend upon how much of the area of the metering slot 49 is above the transverse wall 46.

The valve member 43 preferably has a stem portion 50 that extends substantially vertically, and an upper end portion thereof preferably projects externally of the casing 1 through the top wall or cover 2. Any suitable mechanism, such for example as a cam and cam follower (not shown), may be provided to obtain gradual rectilinear movement of the valve 43 to change the rate of flow of liquid, and this mechanism may be enclosed in a housing 51 in the form of a hollow boss that may surround the valve stem 21 and be integral with the casing cover 2. An upper end portion of the valve stem 21 projects above the housing 51 and secured thereto there may be provided a knob 52 for conveniently rotating the valve 43. Carried by the knob 52 there may be provided a pointer 53 for cooperation with indicia that may be provided on the casing cover to aid in positioning the valve to obtain a desired rate of flow of liquid from the chamber 4. Surrounding the valve 43 within chamber 4 there is preferably provided a helical coil spring 54 having one end abutting an upwardly facing shoulder 54^a formed on the valve member 43 and the other end abutting the underside of the housing or boss 51. The spring 54 is under compression acting to move the valve member 43 downwardly or toward closed position. The operation of the herein described device

is as follows: My liquid level control device may, among other uses, be employed to control flow of fuel, by gravity, to a burner (not shown). Assume that the outlet valve 43 is open to permit flow from the chamber 4 and that the level of the liquid in chamber 4 is at the level L—L, which may be taken as the desired level. At this level the float 23 holds the inlet valve 17 on its seat. Also assume that the level of the liquid in the inlet chamber 5, indicated by the level L'—L', is at the lower edge of the inlet opening of the conduit 34. Now on slight decrease in the level of the liquid in outlet chamber 4 the float 23 will descend and will move the valve 17 slightly away from its seat, which will permit additional liquid to enter the inlet chamber 5. This will of course raise the level of the liquid in chamber 5 and when the level of the liquid reaches the opening of the conduit 34, liquid will flow from the inlet chamber 5 down through the conduit 34 into the receptacle 33. At first the rate of flow of liquid from the inlet chamber 5 into the receptacle 33 will be very small, but the weight of the small amount of liquid in the receptacle 33 will further depress float 23 which will move the valve 17 further away from its seat. Thus, as the float 23 descends in accordance with the increasing quantity of liquid in the receptacle 33, the float 23 moves the valve 17 with acceleration toward open position until the port 16 is wide open, or open to a position in which the rate of inflow is greater than the rate of outflow from chamber 4. Thus it will be noted that the rate of inflow will alternate between a rate of flow less than that of the outflow and a rate of flow greater than that of the outflow. Liquid flowing into receptacle 33 will have the same effect as liquid flowing into chamber 4 for the reason that float 23 will be depressed to a point where it will displace the same amount of liquid as flows into receptacle 33. As is well known, if the rate of inflow to a chamber be greater than the rate of outflow, there will of necessity be an increase 45 of liquid in said chamber. However, because during the period when the flow rate is increasing there is, by the construction employed, an increasing rate of increase making the relatively wide-open position of valve 17 of a very short duration and only sufficient to fill receptacle 33, the amount of liquid required to fill receptacle 33, divided by the area of chamber 4, makes for an inappreciable increase of liquid level in chamber 4. When the receptacle 33 has received a predetermined amount of liquid, such that the weight of the liquid overcomes the spring 40, then the receptacle 33 will pivot in a counter-clockwise direction, as seen in Fig. 2, and will dump or discharge the liquid therefrom into the constant level chamber 4. After discharge of the liquid from the receptacle 33 into the chamber 4, the spring 40 returns the receptacle to its "up" position. Discharging or dumping of the liquid from the receptacle 33 into the chamber 4 will not increase the level of the liquid in the chamber for the reason that when the liquid is discharged from the receptacle 33 the float 23, being relieved of the weight of liquid in receptacle 33, will endeavor to rise to a point where the liquid displacement of the float is decreased by the amount of the liquid dumped from the receptacle 33 into chamber 4. By the float 23 suddenly rising, the valve 17 will be quickly brought against its seat and further inlet of liquid will be prevented until, by flow through the outlet valve 43, there has been a slight reduction in level of liquid in chamber 4, which repeats the cycle previously described. Thus it will be noted that in my device the inlet valve 17 is not throttled or maintained in a position 5 to permit a constant rate of inflow equal to outflow, as is the case in previously known float actuated valves but instead, the valve is moved cyclically between a position in which no inflow occurs, or less than the rate of outflow from the chamber 4, to a position in which the rate of inflow is greater than the rate of outflow from chamber 4. By increasing the rate of inflow through the relatively large opening of valve 17, dirt or foreign matter which may have collected 10 at the seat is permitted to escape through the increased opening of the valve 17. By the continued movement up and down of the valve 17 on its seat 16, the valve is kept clean and deposit at this point of grease or other matter is prevented. Grease or foreign matter collecting on the seat or lodged in the orifice between the valve and its seat may prevent valve closure or proper regulation, thus permitting an undue increase 15 of liquid level in the constant level chamber. Thus my inlet valve 17 is operable in a manner to prevent the lodging and accumulation of foreign matter on its seat and, at the same time, maintains a substantially constant liquid level 20 in the chamber 4.

Referring now to Fig. 3, the device shown includes a hollow casing 55 having a chamber 56 for liquid, the top wall of the chamber being formed by a removable closure member or cover 57. Through the cover 57 there is an inlet passage 58 having a downwardly facing port and valve seat 59 for cooperation with a valve member 60 in the casing chamber 56. The valve member 60 may have an upwardly directed seating surface or face 61 which may be conical, or other suitable form. The valve member 60 is carried by a lever member 62 in the casing chamber 56, and the lever 62 is preferably carried by and removable with the cover 57. The lever member 62 may be pivoted at one end thereof by 40 a pin 64 to a supporting member 63 that may be rigidly secured to and depend from the cover 57 into the chamber 56. In the present instance, the lever 62 has an end portion 65 adjacent its fulcrum that extends substantially horizontally, and through this portion of the lever there is preferably provided an aperture 66 for receiving a lower end portion 67 of the valve member 60, which may have a downwardly facing annular shoulder 68 for seating on the upper surface of the lever 62. The valve member 60 may be loosely supported on the lever 62, the aperture 66 preferably being sufficiently larger than the diameter of the valve reduced portion 67 so that the valve may have a slight predetermined, lateral or side movement relative to the lever 62. Adjacent its other or free end the lever 62 has a downturned portion 69, and rigidly secured to the free end of the lever 62, within the chamber 56, there is a float 70 that is preferably located beneath the valve 60. Disposed immediately beneath the valve member 60, between the valve and the float 70, there is a container or dump bucket 71 into which liquid discharges from the inlet 58. The container 71 may be rigidly secured at one end thereof to one side or leaf 72 of a hinge member, the other side or leaf 73 of which is preferably rigidly secured to the downturned lever portion 69. The container 71 is shown in its "up" position and is yieldably held 75

in this position by a tension spring 74, one end of which may abut the top of the float 70 and the other end of which may abut the underside of the container 71. It will be seen that the 5 valve 60, lever 62, float 70 and container 71 are readily removable as a unitary structure from the casing 55 on removal of the casing cover 57. Through the bottom wall of the casing 55 there is an outlet passage 75 that is preferably controlled by a valve 77 having a metering aperture 76 to determine the rate of flow of liquid from chamber 56. This valve structure may be the same as that shown and described in the device of Figs. 1 and 2, or any other suitable outlet 10 structure may be employed. The device of Fig. 3 differs from that of Figs. 1 and 2 in that only a single chamber is required and the incoming liquid is discharged directly into the container 71 instead of being conveyed thereto, such as by 15 means of a tube 34, Fig. 2. Preferably the lever 62 has apertures 77^a at either side of the valve member 60 so that the lever will not obstruct flow of liquid to the container. The device shown in Fig. 3 operates the same as that previously described in connection with the device of Figs. 1 20 and 2.

In Fig. 4 there is shown a modified inlet valve structure having an inlet passage or bore 78 having a downwardly facing valve port and seat 30 79. The passage 78 preferably opens downwardly into a larger passage or bore 80 provided in a boss 81 that depends from and may be integral with the casing cover 57, and the boss 81 has a lower end wall provided with an aperture or 35 bore 82 which slidably receives and guides a valve member 83. The valve member 83 extends upwardly into the chamber 80 and its upper end may have a conical face or seating surface for cooperation with the seat 79. The valve member 40 83 is provided with a centrally disposed passage or bore 84 that extends longitudinally thereof and the valve may have one or more laterally extending passages or bores 85 to connect the chamber 80 to the passage 84 in the valve. When 45 the valve member 83 is in open position, or away from its seat 79, liquid enters the chamber 80 and flows through the passages 85 into the valve passage 84 and discharges at the lower end of the passage 84 directly into the container 71.

50 Referring now to the modified form of my device, Fig. 5, this device includes a casing 87 formed in part by a bottom wall 88, end walls 89, 90 and a top wall 91. The top wall 91 is preferably formed by a removable closure member or cover that may be held in place by screws 92, or by other suitable means. The casing 87 has an inlet chamber 93 and an outlet or constant level chamber 94 separated by a partition 95. Preferably the partition 95 has two relatively 55 spaced, vertical walls 96, only one of which is shown, and has a vertical wall 97 that joins with the walls 96. The inlet chamber 93 is formed by the walls 96 and 97, together with a portion of the casing end wall 89 with which the spaced walls 96 join. The walls 96 and 97 may be integral with the casing bottom wall 88 and extending upwardly therefrom terminate below or in spaced relation to the underside of the casing cover 91. The constant level chamber 94 has an 60 outlet passage 98, preferably through the casing bottom wall 88, the outlet 98 preferably including a reduced bore 98^a that slidably receives a valve member 99 provided with a metering aperture 99^a to regulate and control the rate of flow 65 of liquid from the chamber 94. As shown in the 75

drawings, the outlet valve structure is the same as that shown in Figs. 1 and 2 but other suitable outlet structure may be employed if desired.

The inlet chamber 93 has an inlet passage 100 including an upwardly facing port and seat 101 5 for cooperation with a reciprocal valve member 102. A float 103 is disposed in the constant level chamber 94 and is operatively connected to the valve member 102, preferably by a lever 105. The lever 105 may be similar in shape to the lever 24 10 of the device shown in Figs. 1 and 2, having an upwardly directed, offset or bent portion 106 intermediate its ends to extend over and clear the partition wall 97. Also, the lever 105 may be pivoted, as at 107, to the side walls 96 of the partition 15 95.

Through the partition wall 97, above the liquid level in the chamber 94, there is a passage 108 for flow of liquid from the inlet chamber 93 into the constant level chamber 94, and the flow capacity of the passage 108 is preferably greater than the flow capacity of the inlet port 101. The passage 108 includes a port and seat 109 that preferably face inwardly of the inlet chamber 93, and the port 109 is controlled by a valve member 110 which is preferably a needle type valve that may be arranged to move horizontally. Preferably the valve member 110 has an extended portion 111 that extends through the passage 108 30 and has a laterally extending abutment or pin 112 in chamber 94 for abutment with the partition wall 97 to limit movement of the valve 110 away from its seat 109.

35 Preferably the valve member 110 is actuated by an overcenter, snap-acting mechanism which may include a lever or link 114 acted on by a helical tension spring 115. The lever 114 is preferably pivoted at one end, above the valve 110, to a movable connecting member 117 which 40 operatively connects the lever 114 to the valve member 102. At its lower end the lever 114 may be provided with an elongated aperture extending longitudinally thereof to receive a pin 118 rigid with and extending laterally from the valve 45 110. The spring 115 may have one end secured to the lever 114, intermediate the ends thereof, and the other end of the spring may be secured to a pin or rod 120 that may be disposed above the upper end of the lever 114. The rod 120 50 may have one end thereof secured in and to the partition wall 97 and may extend longitudinally of the casing 87, or parallel to the walls 96 of chamber 93. At its upper end the connecting member 117 is provided with an aperture or bore 55 to receive the rod 120 on which the connecting member 117 is slidably supported for movement longitudinally thereof.

The valve member 102 preferably has a vertically 60 extending stem portion 121, and preferably rigidly connected to the upper end of the stem portion 121 within the inlet chamber 93 there is a float 122. The overcenter mechanism is operated to actuate the valve 110 on predetermined movement of the valve 102, and to this end the 65 valve stem 121 may be provided, below the float 122, with a cam groove or slot 123 to receive a follower member or pin 124 that may be secured to the lower end of the slideable connecting member 117. 70

The herein described device shown in Fig. 5 operates as follows: Assume that the level of the liquid in chamber 94 is at the desired level L—L, or level at which the valve 102 will be seated, as shown, and also assume that the level of the liq- 75

uid in the inlet chamber 93 is at the level designated L—L'. In operation of the device the outlet valve 99 will, of course, be in an open position to obtain a desired regulated rate of flow of liquid from the chamber 94 less than the rate of flow into inlet chamber 93 when the port 101 is wide open. When the level of the liquid in chamber 94 decreases, the float 103 will descend and move the valve 102 slightly away from its seat 101 to thereby permit additional liquid to enter the inlet chamber 93. The entrance of additional liquid into the inlet chamber 93 will, of course, increase the liquid level therein which causes an increase in the upwardly directed, buoyant force acting on the float 122 with the result that the float 122 now aids the other float 103 to move the valve 102 further away from its seat 101. The increase in the buoyant force acting on the float 122 also results in an increase in liquid displaced by the float 103, with corresponding increase in liquid level in the chamber 94. During the upward movement of the valve 102 the connecting member 117, having its follower 124 in the valve cam groove 123, is moved to the right, which pivots lever 114 in a clockwise direction. On predetermined movement of the connecting member 117 the pivot point of the lever 114 is moved overcenter whereby the spring 115 acts to pivot lever 114 and move valve 110 away from its seat 109 with increasing acceleration, or with a so-called snap action. Liquid now flows from chamber 93 through passage 108 into the constant level chamber 94. The rate of flow of liquid into the chamber 94 is greater than the rate of flow therefrom, with the result that the liquid level begins to rise therein. For a time interval following opening of the valve 110 the float 122 will continue to aid the larger float 103 to hold the valve 102 open. However, as the liquid level decreases in chamber 93 the upward buoyant force on the float 122 decreases, and consequently the effective weight thereof acting to close the valve 102 increases. During this time the float 103, aided by the float 122, moves the valve 102 toward its seat 101. As the valve 102 is moved toward its seat the connecting member 117 is moved to the left, pivoting lever 114 in a counterclockwise direction. When the pivot point of the lever 114 is moved overcenter, the spring 115 will pivot the lever with a quick or snap action and close or seat the valve 110 when the liquid level in chamber 94 is substantially at the desired level L—L'. The above operation is repeated each time the level of the liquid in chamber 94 decreases sufficiently to result in opening of the valve 102 by the float 103. In the device of Fig. 5, like that of Figs. 1 and 2, the valve is not throttled but instead is cyclically moved from its seat to a position where the rate of inflow to chamber 94 is greater than the rate of outflow therefrom, and is then moved to a position or seated position where the rate of inflow is zero, or less than the rate of outflow from chamber 94.

In Fig. 6 the control device embodies a hollow casing 130 having a top cover or closure member 131 which may be secured in position on the casing by bolts or screws 132. This embodiment has an outlet port fitting 133 controlled by a manually adjustable metering valve 134 similar to that described in connection with Fig. 2. The interior of the casing 130 is divided into an inlet chamber 135 and a constant level chamber 136 by a partition or transversely ex-

tending wall member 137 which terminates at its upper end, as at 138, below the top edge of the casing 130. The partition 131 is preferably substantially of the form shown in connection with the foregoing figures, and may be referred to as substantially U-shaped in horizontal cross section so that the side walls of the partition 137 are spaced from the side walls of the main casing 130, but the inlet chamber 135 has a wall in common with the end wall of casing 130. The casing 130 is provided with an inlet fitting 139 having a passageway 140 extending therethrough, and opening at its inner end through a hollow boss or extension 141 rising from the bottom wall of the inlet chamber 135. The passageway 140 receives a valve fitting 142 which is positioned within the chamber 135 and secured, as by screw threaded engagement, in the open inner end of the passageway 140. The fitting 142 has a longitudinally extending bore 143 which is of reduced cross sectional area at its lower end to provide a valve seat and inlet port, and above the port there is one or more transverse passageways or ports through the fitting wall for establishing communication between the bore 143 and the chamber 135. Within the bore 143 there is a valve member 144 which is longitudinally reciprocal therein to control flow through the inlet port. The valve member 144 projects from the upper end of the fitting 142 and is provided with a circumferential groove or recess providing oppositely positioned shoulders between which extends one end of an operating lever 145 which on pivotal movement acts to raise or lower the valve member 144. This lever 145 is formed with an offset portion 146 which bridges the partition 137 and has secured to its free end, within chamber 136, a float member 147 which is responsive to the liquid level in the chamber 136. The lever 145 is pivotally supported, as at 148, on pins or bearing members which are secured in the opposite side walls of the partition 137, the lever 145 having an extension 149 which receives the pivot pins. The chambers 135, 136 are in communication with each other through a siphon tube 150 having its shorter leg within chamber 135 and its longer leg within chamber 136. The tube 150 has a bore diameter less than the diameter of the inlet port in fitting 142, and also has its cross-sectional flow area greater than the effective maximum flow area through outlet 133.

The device shown in Fig. 6 operates as follows: When the chamber 136 is empty, or the liquid level therein is below the desired, predetermined, substantially constant level, the float 147 will be in a down position below that shown in Fig. 6, so that the valve member 144 will be raised from its seat to permit liquid to flow into chamber 135 through passageway 140. As the liquid entering the chamber 135 rises to the level of the line X, it will start to overflow through the siphon tube 150 into the chamber 136, but the liquid level in chamber 135 will continue to increase and when the valve member 144 has opened a predetermined distance, the rate of inlet of liquid through passageway 140 will be greater than the rate of outflow through siphon tube 150 at its maximum rate of flow. As the liquid flows into chamber 136, the float 147 will be lifted by the rise in liquid level and will, through its lever 145, start movement of the valve member 144 toward closed position. However, this movement will not affect the rate of flow through passageway 140 until the liquid level in

chamber 136 has risen substantially to the desired liquid level at the line L. Upon the liquid level rising to the line L, the valve member 144 will be moved to closed position. During the time that the liquid level in chamber 136 has been rising to the line L, the level of liquid in chamber 135 will have risen to a point above the top of the siphon tube 150, thereby filling the tube. As the float member 147 is being lifted, due to the liquid level increasing toward the line L, the valve member 144 will be moving toward closed position throttling the rate of inlet of liquid into the chamber 135 so that the level of liquid in chamber 135 will not increase above a predetermined level below the top edge of partition 131. Obviously, as the valve member 144 moves to its seat, the rate of inflow of liquid to chamber 135 will be less than the rate of flow through siphon tube 150 until the flow through tube 150 ceases. In the event that the liquid outflow through the tube 150 should not keep the liquid level in chamber 135 from rising above the predetermined level, then if the liquid should overflow the partition edge 138, the control device will function in accordance with the prior art constant level controls in which the inlet valve has a throttled position under control of the float member 147 as determined by the rate of outflow from outlet 133. Upon closure of the valve member 144, the siphon tube 150 will then function to continue the discharge of liquid from chamber 135 into chamber 136, but by reason of the relatively greater size of chamber 136 the volume of liquid siphoned out of chamber 135 will cause only a slight rise of liquid level above the line L in chamber 136. This increase of liquid level in chamber 136 will be insufficient to cause any material variation in the liquid head on the outlet 133, and the rate of flow through outlet 133 will therefore remain substantially constant irrespective of this slight change in liquid level. If the liquid level in chamber 136 drops below the line L for any reason, such as consumption of the oil or liquid supplied by or from chamber 136, the float member 147 will start to open the valve member 144, but as the liquid in chamber 135 has been lowered to or below the lower end of the shorter leg of the siphon tube 150, no liquid will be fed into the chamber 136. Therefore the valve member 144 will be moved toward open position in accordance with the decrease of liquid level in chamber 136, and when the liquid level in chamber 136 has decreased to a point which will provide substantially full opening of the valve member 144 with respect to its port, the liquid level in chamber 135 will have risen to a point above or just above the top of the siphon tube 150, and the operation above described by which the liquid is siphoned from chamber 135 into chamber 136 will be repeated. The lever mechanism interconnecting the valve member and the float member is so constructed that full opening of valve member 144 will be effected by a very slight decrease of liquid level in chamber 136 below the line L so that the range between the minimum and maximum levels in chamber 136, during supply of liquid in normal operation through the outlet 133, will be insufficient to deleteriously affect the flow from the outlet, which flow may for all commercial usage be considered constant. The inlet port or passageway 140 is of a size such that when the valve member 144 is in maximum open position, the rate of inflow to the interior 70 of the casing 130 will be greater than the rate

of outflow through outlet 133 when the metering valve 134 is in wide open position.

What I claim and desire to secure by Letters Patent of the United States is:

1. In a liquid level control device, a casing 5 having a chamber with an inlet and outlet means, a valve controlling said inlet, a float operable to move said valve toward closed position, and means cooperable with said float and for receiving and isolating the liquid admitted by said valve, said 10 last-named means acting to decrease the effective buoyancy of said float in accordance with the quantity of liquid admitted by said valve.

2. In a liquid level control device, means providing a chamber having an inlet and an outlet 15 for liquid, a valve controlling said inlet, a float operatively connected to said valve and operable in response to the liquid level in said chamber, and a receptacle into which liquid flows and operable to isolate the incoming liquid from 20 said chamber, means cooperable with said receptacle and operable subsequent to receiving a predetermined quantity of liquid to discharge the liquid into said chamber, said receptacle and liquid delivered thereto cooperating with said float 25 to vary the buoyancy of said float.

3. In a liquid level control device, means providing a chamber for liquid and having an inlet and an outlet therefor, a receptacle to which liquid is supplied, means operable solely subsequent to said receptacle receiving a predetermined quantity of liquid to allow the liquid to flow from said receptacle into said chamber, a float responsive to changes in liquid level in said chamber and carrying said receptacle, and valve 30 means controlling said inlet and actuated by said float to control supply of liquid to said receptacle.

4. In a liquid level control device, means providing a chamber for liquid and having an outlet, means providing an inlet chamber associated 40 with said first-named chamber and having an inlet, valve means controlling said inlet, a float responsive to changes in liquid level in said first-named chamber and operatively connected to said valve means, a receptacle carried by said 45 float and to which liquid is supplied from said inlet to vary the effective buoyancy of said float, and means operable solely subsequent to said receptacle receiving a predetermined quantity of liquid to discharge the liquid from said receptacle 50 into said first-named chamber.

5. In a liquid level control device, a casing having a chamber wherein the level of a liquid is maintained at a predetermined substantially constant level, said chamber having an inlet and an outlet for liquid, a valve controlling said inlet, a float for actuating said valve and responsive to changes in the level of the liquid in said chamber, said float being only partially submerged in the liquid when the level thereof is at said substantially constant level, a receptacle carried by said float and communicatively connected to said inlet, said receptacle being operable to isolate the incoming liquid from said chamber, said float on decrease in liquid level in said chamber being operable to increase the rate of flow of liquid into said receptacle and being further submerged by and in accordance with the increasing weight of liquid in said receptacle 60 to move said valve further toward open position, and means operable to discharge the liquid from said receptacle into said chamber solely subsequent to a predetermined quantity of liquid being received by said receptacle, said float on dis- 75

charge of liquid from said receptacle moving said valve to close said inlet.

6. In a liquid level control device, a casing having a chamber wherein the level of a liquid is to be maintained at a substantially constant level and having an outlet for said chamber, said casing also having an inlet chamber and an inlet therefor, a receptacle to which liquid is supplied from said inlet chamber, duct means for conveying liquid by gravity from said inlet chamber for discharge into said receptacle, said receptacle being operable to isolate the supplied liquid from said chamber, means for periodically discharging said liquid from said receptacle into said first-named chamber, a float responsive to liquid level changes in said first-named chamber and carrying said receptacle, and valve means controlling said inlet and operatively connected to said float.

7. In a liquid level control device, a casing having a constant level chamber for liquid and having an inlet and an outlet, valve means controlling said inlet, a float responsive to changes in liquid level in said chamber and operatively connected to said valve means, a receptacle carried by said float and communicatively connected to said inlet, hinge means connecting said receptacle to said float, said float on decrease in liquid level in said chamber moving said valve toward open position to supply liquid to said receptacle to affect the float to move said valve further toward open position, said receptacle on receiving a predetermined quantity of liquid pivoting to discharge the liquid into said chamber, and yieldable means opposing pivotal movement of said receptacle.

8. In a liquid level control device, a casing having a constant level chamber and an outlet therefor, said casing also having an inlet chamber and an inlet therefor, a valve controlling said inlet, a float responsive to changes in liquid level in said first-named chamber and operatively connected to and for actuating said valve, a receptacle pivotally mounted on and carried by said float, duct means communicatively connecting said receptacle and said inlet chamber, said duct means communicating with said inlet chamber above the level in said first-named chamber, said float on decrease in liquid level moving said valve toward open position to increase the liquid level in said inlet chamber for flow to said receptacle, said float being affected by the increased weight of the liquid in said receptacle to further open said valve, said receptacle on receiving a predetermined quantity of liquid being operable to pivot and discharge the liquid into said first-named chamber, said float on discharge of liquid from said receptacle moving said valve toward closed position, and resilient means yieldably opposing pivotal movement of said receptacle.

- 60 9. In a liquid level control device, a casing having a relatively large constant level chamber and a relatively small inlet chamber, said constant level chamber having an outlet and said inlet chamber having an inlet, a valve controlling said inlet, a float for actuating said valve and responsive to changes in liquid level in said constant level chamber, a receptacle carried by said float, means communicatively connecting said inlet chamber and said receptacle, said float on decrease in liquid level in said constant level chamber unseating and moving said valve toward open position so that liquid will flow into said receptacle, said float being moved by and in accordance with the increasing weight of the liquid in said receptacle to move said valve further to-

ward open position, and means operable solely subsequent to said receptacle receiving a predetermined amount of liquid to allow the liquid to discharge from said receptacle into said constant level chamber so that said float can act to seat said valve.

10. In a liquid level control device, a casing having a chamber for liquid and having an inlet valve port above the liquid level to be maintained in said chamber, a valve member to control said port, a float in said chamber and operatively connected to said valve member, a container carried by said float beneath said port to receive liquid to affect operation of said valve member by said float, and means operable upon the occurrence of a predetermined quantity of liquid in said container to discharge the liquid into said chamber.

11. In a liquid level control device, a casing having a chamber for liquid and having an opening thereto, a removable closure member closing said opening and having an inlet port opening into said chamber above the liquid level therein, a lever member carried by said removable closure member, a float attached to said lever member and responsive to changes in liquid level in said chamber, a valve carried by said lever member and controlling said port, a container carried by said lever member and arranged to receive liquid from said inlet, and means operable to discharge the liquid from said container into said chamber, said lever member, said float and said container being removable from said casing with said closure member as a unitary structure.

12. In a liquid level control device, a casing having a liquid level chamber and a second chamber, said second-named chamber having an inlet port, a valve member to control said port, a float responsive to changes in liquid level in said first-named chamber and operatively connected to said valve member, said chambers being connected by a passage including a valve port, a valve member controlling said second-named port, a float responsive to changes in liquid level in said second-named chamber and operatively connected to both of said valve members.

13. In a liquid level control device, a casing having a chamber for liquid and having an outlet, said casing having an inlet chamber separated from said first-named chamber by a partition and having an inlet port, a valve member in said inlet chamber and controlling said port, a float in said first-named chamber and operatively connected to said valve member, a passage through said partition connecting said chambers and having a port above the liquid level in said first-named chamber, a valve member to control said second-named port, a float carried by said first-named valve member and cooperable with said first-named float to move said first-named valve member toward open position, and means operable on predetermined opening movement of said first-named valve member to open said second-named valve member.

14. In a liquid level control device, a casing having a chamber for liquid and having an outlet, said casing having an inlet chamber separated from said first-named chamber by a partition and having an inlet port, a valve member in said inlet chamber and controlling said port, a float in said first-named chamber and operatively connected to said valve member, a passage through said partition connecting said chambers and having a port above the liquid level in said

- first-named chamber, a valve member to control said second-named port, a float carried by said first-named valve member and cooperable with said first-named float to move said first-named 5 valve member toward open position, snap-acting mechanism to actuate said second-named valve member, and means to actuate said snap-acting mechanism and operable on predetermined movement of said first-named valve member.
- 10 15. In a liquid level control device, a chambered casing including a constant level chamber and including an inlet to said casing and an outlet therefrom, a liquid displacing means in said chamber responsive to liquid level and controlling 15 said inlet, said displacing means being operable to admit liquid through said inlet to maintain a substantially constant level in said chamber, and means including an inlet chamber for receiving the liquid from said inlet and operable to isolate 20 the incoming liquid from and to discharge the liquid at intervals into said constant level chamber, said last-named means also being operable to move said liquid displacing means thereby to maintain substantially constant the liquid level 25 in said constant level chamber with decrease in liquid volume.
16. In a liquid level control device, a chambered casing including a constant level chamber and including an inlet to said casing and an 30 outlet therefrom, a liquid displacing means in said chamber responsive to liquid level and controlling said inlet, said displacing means being operable to admit liquid through said inlet to maintain a substantially constant level in said 35 chamber, means including an inlet chamber for receiving the liquid from said inlet and operable to isolate the incoming liquid from said constant level chamber, said last-named means also being operable to move said liquid displacing 40 means thereby to maintain substantially constant the liquid level in said constant level chamber with decrease in liquid volume, and means operable to discharge the liquid from the last-named means into said constant level chamber.
- 45 17. In a liquid level control device, a casing having a constant level chamber and an outlet therefor, said casing also having an inlet chamber and an inlet therefor, a valve controlling said inlet, a float responsive to changes in liquid level 50 in said first-named chamber and operatively

connected to and for actuating said valve, a receptacle positioned within said first-named chamber and cooperable with said float, duct means communicatively connecting said receptacle and said inlet chamber, said duct means communicating with said inlet chamber above the level in said first-named chamber, said float on decrease 5 in liquid level moving said valve toward open position to increase the liquid level in said inlet chamber for flow to said receptacle, said float being affected by the increased weight of the liquid in said receptacle to further open said valve, and means operable solely subsequent to a predetermined quantity of liquid being received in said receptacle to discharge the liquid into said 10 first-named chamber, said float on discharge of liquid from said receptacle moving said valve toward closed position.

18. In a liquid level control device, means providing a chamber for liquid and having an inlet 20 and an outlet therefor, a float responsive to changes in liquid level positioned within said chamber, a receptacle positioned within said chamber and pivotally carried by said float, said inlet being operable to discharge into said receptacle, a valve controlling flow of liquid through said inlet and actuated by said float, and means operable solely upon the occurrence of a predetermined quantity of liquid in said receptacle to pivot said receptacle thereby to discharge the 25 liquid from said receptacle into said chamber.

19. In a liquid level control device, means providing a chamber for liquid and having an outlet, means providing an inlet chamber associated with said first-named chamber and having an 30 inlet, valve means controlling said inlet, a float responsive to changes in liquid level in said first-named chamber and operatively connected to said valve means, a receptacle pivotally carried by said float and to which liquid is supplied from 35 said inlet to vary the effective buoyancy of said float, said receptacle having a liquid holding position and a liquid discharging position, and means operable to hold said receptacle in said holding position, said means being operable to allow 40 movement of said receptacle to said discharging position subsequent to the liquid in said receptacle reaching a predetermined quantity.
